UNITED STATES PATENT OFFICE.

WALTER W. BRISSON, OF NORWAY, MICHIGAN.

SWITCH CLEANER.

Application filed October 2, 1923. Serial No. 666,138.

To all whom it may concern:

Be it known that I, WALTER W. BRIS-
SON, a citizen of the United States, residing
at Norway, in the county of Dickinson and
5 State of Michigan, have invented a new
and useful Switch Cleaner, of which the
following is a specification.

This invention has reference to an attach-
10 ment to be used in connection with loco-
motives or the like, the primary object of
the invention being to provide means for
cleaning snow and ice from the track to
insure against snow and ice clogging
15 switches to render the switch inoperative.

Another object of the invention is to pro-
vide a device of this character which may
readily and easily be thrown into operation
by the engineer in the cab.

A still further object of the invention is
20 to provide means for automatically moving
the device to its inactive position after it
has been operated to accomplish its pur-
pose.

With the foregoing and other objects in
25 view which will appear as the description
proceeds, the invention resides in the com-
bination and arrangement of parts and in
the details of construction hereinafter de-
scribed and claimed, it being understood
30 that changes in the precise embodiment of
the invention herein disclosed, may be made
within the scope of what is claimed, with-
out departing from the spirit of the inven-
tion.

35 Referring to the drawing:

Figure 1 is a fragmental elevational view
disclosing the forward end of a locomotive
and showing an attachment constructed in
accordance with the invention as positioned
40 thereon.

Figure 2 is a bottom plan view of the at-
tachment.

Figure 3 is a side elevational view dis-
closing a pair of nozzles for directing steam
45 to the track.

Figure 4 is an enlarged detail view dis-
closing the operating lever for controlling
the nozzles.

50 Referring to the drawings in detail, the
device embodies a horizontally disposed
pipe 5 which is mounted in the bearings 6
that are secured to the supporting bars 7
that are arranged at the rear of the cow-
catcher 8, and in front of the wheels 9.

55 Pipes 10 communicate with the pipe 5

through the elbows 11, which pipes have
connection with the downwardly extended
pipes 12, as by means of the union 13. At
the lower ends of the pipe 12 are nozzles
14 which nozzles are removably supported
60 by means of the threads 15 that cooperate
with threads formed internally of the nozzle
14.

Steam is fed to the pipe 5 through the
hose 16 that has connection with the pipe 5
65 through the T union 17, which hose 16 com-
municates with a suitable source of steam
supply, there being provided a valve not
shown, for controlling passages of steam
through the hose 16 and pipe 5, it being
70 understood that the valve is located adja-
cent to the engineer's seat, so that the en-
gineer will have easy access thereto.

Due to the construction of the pipe 5 and
its bearing member, it is obvious that the
75 pipe 5 may rotate or move slightly to cause
the nozzles 14 of the pipes 12 to move
within proximity to the rails over which the
locomotive is moving, and to this end an
arm 18 is provided which arm has connec-
80 tion with the pipe 5 to cause the pipe 5 to
move when the arm 18 is to be moved.
This arm 18 moves within the guide 19,
the curved extremity thereof acting as a
85 stop for the arm 18 to prevent the nozzles
from being lowered into contact with the
ties of the track construction.

In order that the arm 18 may be con-
trolled by the engineer, a rod 20 is supplied,
which rod has connection with the arm at
one end thereof, the opposite end of the
rod being disposed adjacent to the en-
90 gineer's seat.

Coiled around the pipe 5 is a spring 21
that has one end thereof looped around the
union 17 as at 22, the opposite end of the
spring being anchored at 23 so that when
the pipe has been partially rotated to move
the nozzles to accomplish the purpose of
the invention, the spring 21 will be placed
100 under tension, so that when the rod 20 is
released by the engineer, the pipe 5 together
with its nozzles will be moved to bring the
nozzles to their inactive positions or to po-
sitions as shown by Figure 1 of the draw-
ings.

In the use of the device, assuming that
a switch or frog becomes clogged with snow
and ice it is only necessary for the engineer
to pull the rod 20 to throw the nozzles 14
110

Pipes 10 communicate with the pipe 5

into proximity with the switch, whereupon the steam valve is operated to allow steam to pass through the pipe 5 and nozzles associated therewith to the end that the steam will melt the ice and snow and allow the switch to be operated.

I claim:—

In a device of the character described, a pipe disposed in a horizontal plane and 10 rotatable on its axis, rearwardly extended pipes connected with the first mentioned pipe, downwardly extended pipes having connection with the last mentioned pipes and carrying nozzles on their free ends, a 15 spring coiled around the first mentioned

pipe and acting thereon to hold said nozzles in their normal inoperative positions, means for rotating the first mentioned pipe to move said nozzles downwardly to operative positions, means for restricting the rotary movement, and means for supplying steam to said first mentioned pipe. 20

In testimony that I claim the foregoing as my own, I have hereto affixed my signature in the presence of two witnesses.

WALTER W. BRISBON.
